BURNETT C. BOOTH, OF LOS ANGELES, CALIFORNIA

LINEMAN'S PLATFORM

Application filed June 25, 1928. Serial No. 288,256.

This invention relates to a platform or scaffold adapted to be secured to a pole or other vertical body, particularly for use by linemen in their work on the poles of electric power transmission lines and the like.

An important object of the invention is to provide a platform of strong and rugged construction which is adapted to be firmly secured to a pole in any desired position, while permitting ready removal therefrom when desired. A particular object of the invention is to provide for securing of the platform to the pole in such manner as to firmly support the weight of a person thereon, and to prevent accidental displacement from the pole, and especially to prevent lateral swinging of the platform about the pole. A further object of the invention is to provide improved means for tightening the securing means in position about the pole so as to tightly embrace the same.

A further object of the invention is to provide a platform and supporting and securing means therefor of a collapsible construction, so that the apparatus may be collapsed substantially into the plane of the platform to permit ease of handling the same and bringing it into the desired position on the pole, particularly in the presence of cross arms and transmission lines. Certain constructions of linemen's platforms heretofore used have been open to the objection that certain parts of the securing means, consisting usually of metal bars or the like, projected rigidly from the plane of the platform and they were, therefore, awkward to handle and particularly difficult to raise into position above a set of high voltage wires secured to a cross arm. In raising the platform to such position it is necessary to pass the same between the two sets of wires at opposite ends of the cross arms, one or both of which may be at a high potential, and with such a rigid construction there is an obvious danger of short circuiting or even of electrocution of the operator who is handling the apparatus. These disadvantages are overcome according to my invention by making the apparatus collapsible as above mentioned. A further advantage of the collapsible construction is that it may be folded

up in a very compact manner and will take up but little space, when being carried in a truck or other vehicle to the place where it is to be used. This is quite an item, as such truck is usually well loaded with other materials and economy of space is important. 55

A further object of the invention is to make the platform invertible, that is, so that it may be secured in position with the securing means extending either upwardly or downwardly from the platform, and may, therefore, be mounted either directly above or directly below a cross arm. 60

The apparatus comprises a flat platform or board 1 of any desired length and width and formed preferably of wood of the desired strength. Said platform may be rounded in a concave shape at its inner end, that is the end which is to be placed against the pole, as indicated at 2, so as to conform approximately to the usual or average curvature of the poles on which it is to be used. A metal channel bar 3 may be secured over this end of the platform, having substantially the same curvature and being preferably provided with a plurality of prongs or pointed members 4 adapted to be pressed into or against the pole. Stiffening or reinforcing members such as channel bars 5 are also preferably secured over the edges of the platform adjacent the aforesaid end thereof and extending throughout any desired portion of the length of the platform, and preferably to a sufficient distance to receive the ends of the inclined supporting or bracing members hereinafter described. The channel members 3 and 5 are preferably secured together as by welding, as indicated at 6. 80 85

A further object of the invention is to provide an apparatus having adjustable securing means so as to render it adaptable to poles of different sizes. 90

A further object of the invention is to provide in connection with a lineman's platform, 95 an insulated stand which may be quickly secured upon the platform or detached therefrom, so as to permit the lineman to work in safety upon high voltage lines. A particular object in this connection is to adapt the same

insulated stand to use upon the ground or in other positions.

The accompanying drawings illustrate a preferred embodiment of my invention and the manner of securing the same to a pole, and referring thereto.

Fig. 1 is a side elevation of the platform, with the insulated stand mounted thereon.

Fig. 2 is a plan view thereof.

Fig. 3 is an end elevation taken from the left in Fig. 1.

Fig. 4 is a section on line 4—4 in Fig. 1.

Fig. 5 is a perspective view showing 2 platforms according to this invention mounted in respective inverted positions on a pole.

Fig. 6 is a perspective view of the apparatus with the securing means collapsed against the platform.

Fig. 7 is a perspective view of the insulated stand showing the manner of using the same separately from the platform, for example upon the ground.

A pair of supporting bars 7 are pivoted as at 8 at the respective side of platform 1 and adjacent the inner end of said platform so as to be adapted to swing from a position against or alongside the platform and substantially in the plane thereof as shown in Fig. 6 to an upright or vertical position, as shown for example, in Figs. 1, 3 and 5. Two bracing bars or members 10 are pivotally mounted at the ends of the respective bars 7 as by means of a transverse rod 11 extending through said members as shown in Fig. 3, said bars being spaced in suitable relation thereon by means of nuts or other spacing members 12. The bracing bars 10 are provided at their free ends with openings 13 adapted to engage projecting studs or pins 14 at the respective sides of platform 1, when the bars 7 are swung to vertical position, said pins 14 being secured, for example, to the respective side bars 5. When so engaged said bars may be held in position by means of retaining pins 16 passing through openings 17 in the respective studs 14, said pins being tied to the platform as by means of small chains 18. The inner ends of the respective bracing bars 10 are preferably pointed as shown at 19 so as to penetrate or grip the pole as hereinafter described.

The means for securing the platform in position may further comprise a flexible securing member such as chain 21 secured at one end as at 22 to a tightening lever 23 pivotally mounted at 24 on bracket 25 at one side of the inner end of the platform and adapted to adjustably engage hook means 26 at the other side of the platform, and another flexible securing member such as chain 27 secured at one end as at 28 to the outer end of one of the bars 7 and adapted to be adjustably connected at its other end to hook means 29 at the lower end of the other bar 7. The chains 21 and 27 are adapted to be passed around the pole so as to embrace the

same and to have a suitable link thereof engaged in the hook means 26 and 29 respectively. The tightening lever 23 is adapted to be swung about its pivot 24 toward or away from the platform and substantially in the plane thereof and may be secured in position against the platform by means of pin 31 passed through openings 32 in a pair of lugs 33 between which said lever is received. The pin 31 may also be tied to the platform as by means of chain 34.

The insulated stand may comprise a platform member 36 secured in suitable manner to four insulating supports 37 disposed in pairs adjacent the respective ends of platform 36 as shown in Fig. 2. The pair of insulating supports 37 adjacent each end of said platform are mounted upon a bar or strap member 38, said bars being adapted to extend across, above and project somewhat beyond the sides of the platform 1. Bars 39 are also provided adapted to extend beneath platform 1 and to project beyond the sides thereof, and means such as threaded pins or bolts 41 and wing nuts 42 may be provided for clamping the platform 1 between the bars 38 and 39 so as to hold the insulated stand firmly in position on said platform. Acorn nuts 43 are also preferably provided on pins or bolts 41 so as to permit the insulated stand to be used in other positions, as upon the ground, without injury to the lower ends of said bolts.

In using the above described platform, the same may be collapsed as shown in Fig. 6, by removal of pins 16 and disengagement of arms 10 from studs 14. The platform may then be raised to the desired height on the pole, it being noted that when so collapsed all of the supporting and securing means are approximately in the plane of the platform and the entire device may, therefore, be easily raised past any conducting wires which may be mounted upon the cross arms 51. The platform may be mounted in either of the positions shown in Fig. 5, that is with the supporting arms 7 and bracing arms 10 either above or below the platform. In securing the device in the position of the upper platform shown in Fig. 5, the arms 7 and 10 may be raised to the desired position and arms 10 may be engaged with studs 14 and held in position by retaining pins 16. The two securing chains 21 and 27 may then be passed around the pole and a suitable link of each chain engaged with the corresponding hook means, 26 or 29, so as to cause the chains to embrace the pole. The chain 27 connecting the outer ends of arms 7 may be secured tightly enough in this manner, but additional tightening of chain 21 may be secured by means of tightening lever 23 as illustrated more clearly in Fig. 2.

For this purpose said lever may first be moved to some such position as indicated in

dotted lines at 23' and the chain 21 may then be passed around the pole and secured to hook 26. By then moving lever 23 to position against the side of the platform, any desired 5 tightening of the chain may be secured, such tightening also serving to force the pointed members 4 into the pole. The tight engagement of chain 21 with the pole and also the engagement of prongs 4 therewith serves to 10 clamp the pole tightly between the platform member and the chain and thus effectively prevent lateral swinging of the platform. When the lever 23 has been brought to position alongside the platform the retaining pin 15 31 may be inserted to hold it in this position. The provision of two securing members adapted to embrace the pole, one substantially in the plane of the platform, and the other at the ends of supporting arms 7 constitutes 20 an important feature of this invention as it effectively holds the platform against falling when in the position above mentioned, while the first-named chain, particularly when tightened as above described, constitutes an especially important feature of the invention 25 as it prevents lateral swinging movement of the platform.

The device may also be mounted as shown at the bottom of Fig. 5, the manner of securing 30 the same to the pole being substantially the same in this case as before. When in this position, however, the pointed ends 19 of the bracing bars 20 engage the face of the pole and hold the platform against falling. 35 The apparatus is, therefore, equally stable when mounted in either of the two relatively inverted positions.

The insulated stand may readily be mounted upon platform 1 when in either of 40 the positions shown in Fig. 5, by loosening the wing nuts 42 and bringing the stand to the desired position on said platform, with the bars 38 and 39 extending respectively above and beneath said platform, and then tightening 45 the wing nuts 42 to hold said stand in such position. The insulated stand may also be used independently of the platform by simply resting the same upon the ground or other surface, as indicated in Fig. 7, the acorn 50 nuts 43 serving as legs in such cases and preventing injury to the threads of pins 41. When used either in connection with the platform or independently thereof, an operator 55 may stand upon the insulated platform 36 and insulators 37 will then prevent passage of electric current through the body of such operator to ground.

I claim:

1. A lineman's platform comprising a platform member, collapsible supporting members mounted adjacent one end of said platform member to swing from position alongside the platform to position perpendicular thereto, collapsible bracing means for holding 60 said supporting members in said last-

named position, and securing means adapted to embrace a pole and hold both the upper and lower ends of said supporting members inwardly against said pole when said supporting members are in position perpendicular to the platform, said supporting members, bracing means, and securing means, being adapted to lie substantially in the plane of 70 said platform when collapsed.

2. A lineman's platform comprising a platform member, a flexible securing member adapted to extend around a pole substantially in the plane of said platform member, means for securing the ends of said securing member to the respective sides of said platform member, two supporting members extending perpendicular to said platform member at the respective sides thereof, inclined bracing members connecting the ends of the 80 respective supporting members to the platform member, said bracing members having their inner ends adapted to engage the pole beneath the level of the platform, when the platform is placed with the supporting members extending downwardly, and hold the 85 platform in horizontal position, a second flexible securing member adapted to extend around the pole, and means for securing said second flexible member to the respective supporting members at a level spaced vertically 90 from the plane of the platform so as to hold said platform in horizontal position when the platform is placed with the supporting members extending upwardly therefrom.

3. In a lineman's platform a platform member having its inner end formed to abut against a pole and provided with prong means adapted to engage in such pole, a flexible securing member adapted to extend entirely around a pole from one side of the 105 inner end of said platform member to the other side thereof, means for connecting the respective ends of said securing member to the inner end of said platform member at opposite sides thereof, and means for tightening 110 said securing member about a pole so as to clamp the pole tightly between said securing member and the inner end of the platform member.

4. In a lineman's platform, a platform member, a lever pivotally mounted at one side of said platform member adjacent the inner end thereof, a flexible securing member secured to said lever at a distance from the point of pivotal support thereof and 120 adapted to extend entirely around a pole to the other side of the platform member, and means for connecting said securing member to said other side of said platform member adjacent the inner end thereof, said lever being adapted to swing from a position projecting outwardly from the platform to a position alongside the platform so as to tighten 125 said securing member about a pole.

5. In combination with a lineman's plat- 130

- form having a horizontally extending platform member, an insulated stand comprising a platform, insulating supports secured beneath said last mentioned platform adjacent to the respective ends thereof, bars secured beneath the insulating supports at the respective ends of said last named platform and adapted to extend across and rest upon the first mentioned platform member, bars extending beneath and spaced from the respective first mentioned bars and adapted to extend beneath said first mentioned platform member and means for clamping said last mentioned bars to said first named bars so as to clamp the first mentioned platform member therebetween, said clamping means having means at their lower ends adapted to rest upon the ground and permit use of said insulated stand separately from said lineman's platform.

6. In a lineman's platform, a platform member having its inner end adapted to fit against a pole, a lever pivotally mounted at one side of said platform member adjacent to said inner end thereof, a flexible securing member substantially unyielding in the direction of its length, secured to said lever at a distance from the pivotal support of said lever and adapted to extend entirely around a pole to the other side of said platform member, and means for connecting said securing member to said other side of the platform member adjacent the inner end thereof, said lever being adapted to swing from a position projecting outwardly from the platform to a position alongside the platform and away from the inner end thereof so as to draw said securing member tightly into engagement about the pole.

40 In testimony whereof I have hereunto subscribed my name this 13th day of June, 1928.

BURNETT C. BOOTH.
